UNITED STATES PATENT OFFICE

151,950

DESIGN FOR AN ACCESSORY KIT

Sidney G. Anderson, San Francisco, Calif.

Application February 28, 1948, Serial No. 144,828

Term of patent 14 years

(Cl. D87—3)

To all whom it may concern:

Be it known that I, Sidney G. Anderson, a citizen of the United States, residing in the city and county of San Francisco, State of California, have invented a new, original, and ornamental Design for an Accessory Kit, of which the following is a specification, reference being had to the accompanying drawing, forming part thereof.

Fig. 1 is a perspective view of an accessory kit, showing my new design in closed position.

Fig. 2 is a front elevation of the kit when open.

Fig. 3 is a front elevation of the kit when open and with the mirror and lights in extended position.

Fig. 4 is a sectional view along the line 4—4 of Fig. 3.

Fig. 5 is a sectional view along the line 5—5 of Fig. 2.

I claim:

The ornamental design for an accessory kit, as shown.

SIDNEY G. ANDERSON.
